Primary Examiner—Ian Simmons
Assistant Examiner—Wan Laymon(57) **CLAIM**

The ornamental design for a weapon aiming device, as shown and described.

DESCRIPTION

FIG. 1 is a perspective view of a weapon aiming device of the present invention;

FIG. 2 is a front view of the weapon aiming device of FIG. 1; FIG. 3 is a rear view of the weapon aiming device of FIG. 1; FIG. 4 is a right side view of the weapon aiming device of FIG. 1;

FIG. 5 is a left side view of the weapon aiming device of FIG. 1;

FIG. 6 is a top view of the weapon aiming device of FIG. 1; and,

FIG. 7 is a bottom view of the weapon aiming device of FIG. 1.

The broken lines in the Figures are for illustrative purposes only and form no part of the claimed invention.

1 Claim, 4 Drawing Sheets
